UNITED STATES PATENT OFFICE.

VERNER A. LONGAKER, OF BOSTON, MASSACHUSETTS.

TRUSS.

Application filed December 4, 1924. Serial No. 753,857.

My invention relates to improvements in trusses, and has for its object to provide a truss which can be conveniently worn in bathing or by persons who perspire profusely.

Other and further objects of my invention will be in part obvious and in part described as this specification is proceeded with.

In the accompanying drawings forming part of this specification:

Figure 1 is a perspective view of a single truss made in accordance with my invention;

Figure 2 is a perspective view showing a modified form of spring casing used with a double truss; and

Figure 3 is a section on the line 3—3 of Figure 1.

Referring again to the drawings wherein like references denote corresponding parts throughout the views, and with special reference to Figure 1 therof, 5 denotes a single truss comprising the frame or spring 6 of ordinary construction.

Completely enclosing the truss frame 6 is a casing 7 preferably of sponge rubber. This casing which is of tubular formation adapted to slip snugly over the spring, and closed at one end as at 8, is provided at its opposite end 9 with an extension or strap 10. In securing the strap or extension 10 to the casing after the casing has been positioned on the spring 6, as by vulcanizing or stitching, the end 9 of the casing is also closed, thus completely protecting the spring from moisture. Screws 11 pass through openings 12 in the casing and screw into corresponding openings 13 in the truss frame or spring. These screws serve the double purpose of preventing relative movement of the truss frame and casing and also provide means for securing the sponge rubber pad 14 in place.

The pad 14 just referred to encloses a steel plate 15 to which an angularly shaped arm

16 is pivoted by means of the screw 17. One end of this arm 16 is formed with a longitudinal slot 17' for the reception of the screws 11 and the other end of the arm is formed with a transverse slot 18 for the reception of the screw 19.

It will be noted that the angularity of the pad 14 with respect to the truss frame or spring 6 and casing 7 can be adjusted by loosening the screw 19 and turning the pad on the pivot screw 17. And by partly unscrewing the screws 11 the truss pad may be moved toward or away from the end 8 of the truss frame or spring casing.

When the truss has been adjusted about the person of the wearer, the free end of the strap or extension 10 is attached to the adjusting screw 19 or to the knob 26 by means of the openings 20 in the strap or extension 10.

In Figure 2 wherein a double truss 21 is illustrated, the truss frame or spring 22 is enclosed at either end by casings 23, which snugly grip the frame so as to prevent ingress of moisture thereto. The casings 23, 70 are secured in place by means of screws 24. Back pads 25, are secured to the frame in any desired manner (not shown).

Having thus described my invention what I claim as my invention is:

In a device of the class described, a truss frame and truss pad, a casing of sponge rubber enclosing said frame and closed at each end, an arm pivotally connected intermediate its ends to said truss pad, said arm having means at its outer end cooperating with means on said pad for limiting the relative pivotal movement of said pad and frame, and means for securing the other end of said arm to the frame, said last mentioned means tending to prevent movement of the casing upon the pad.

In testimony whereof I affix my signature.

VERNER A. LONGAKER.
